UNITED STATES PATENT OFFICE.

HANS GUSTAV JOACHIM DEINERT, OF BIG SPRING, TEXAS.

CHECK-VALVE.

1,311,642.

Specification of Letters Patent. Patented July 29, 1919.

Application filed December 20, 1917. Serial No. 208,130.

To all whom it may concern:

Be it known that I, HANS G. J. DEINERT, a citizen of the United States, residing at Big Spring, in the county of Howard and 5 State of Texas, have invented new and useful Improvements in Check-Valves, of which the following is a specification.

This invention relates to check valves which are interposed between the injector 10 and the boiler of locomotives, and its object is to provide a valve of this kind which will secure a better priming action and a greater forcing power of the injector, and which can be easily disconnected from the boiler 15 for repairs.

With the object stated in view, the invention consists in a novel combination and arrangement of parts to be hereinafter described and claimed, and in order that the 20 same may be better understood, reference is had to the accompanying drawing forming a part of this specification.

In the drawing,

Figure 1 is a longitudinal section of the 25 device;

Fig. 2 is a plan view of the check valve proper, and

Fig. 3 is a plan view of a valve guide.

Referring specifically to the drawing, 5 30 denotes an elongated check valve casing having at one end a seat 6 for the valve 7. The passage leading from the inlet end of the casing to the valve seat is reamed in the form of a nozzle, it being made tapering in 35 the direction of the valve seat, whereby the velocity of the water flowing through the passage is materially increased, which secures a better priming action and a greater forcing power of the injector, and will 40 greatly prolong the life of the nozzle in the injector. The liquid passed forward through the agency of the injector, and headed for the boiler by way of the check valve, loses a portion of its velocity through pipe-friction, pipe-bends, etc. of the boiler feed conduit, and in order to compensate for this 45 loss of velocity and to restore the liquid to the original or initial velocity attained at the injector nozzle, the check-valve nozzle 50 5 has been provided. This nozzle, while somewhat diminishing the volume of the boiler feed water, increases its speed, whereby the life of the injector nozzle is prolonged because the strain of service upon the

latter is diminished. The fact that the nipple or pipe 13 restores the original velocity is of no importance and does not detract from the usefulness of the device, for the reason that once the water has passed the check valve 7 it has no further influence on 60 the injector and cannot react thereon.

The inlet end of the casing 5 is connected by a coupling nut 8 to a nipple 9 by which latter the connection with the injector (not shown) is made.

To the outlet end of the check valve casing 5 is detachably connected the casing 10 of a shut-off valve 11. This casing has a side outlet 12 which is suitably connected to the boiler (not shown).

The connection between the casings 5 and 70 10 is made by a nipple 13 and a coupling nut 14, the latter being screwed on the outlet end of the casing 5 and engaging the usual shoulder or flange on the nipple, and 75 the nipple, in turn, being connected to the casing 10 by being screwed into the inlet end thereof.

Between the shouldered end of the nipple 13 and the adjacent end of the casing 5 is 80 held a guide for the valve 7, this guide being a ring 15 between which and a central hub 16 radial arms 17 extend. The stem 18 of the valve 7 extends slidably through the hub portion of the guide member. The ring 85 portion 15 is shouldered on one side as shown at 19 to seat on the end of the casing 5, and on its other side it has a bevel seat 20 engaged by the beveled end of the nipple 13.

By connecting the two valve casings, as 90 hereinbefore described, the parts can be easily disconnected from the boiler for repairs. The entire structure is also simple and composed of few parts and devoid of parts liable to get out of order.

I claim:

1. A boiler check comprising an elongated casing provided with a fluid passage which is tapered and having means at its larger end for connection to an injector, a valve seat at the smaller end of the passage, a check valve engageable with the seat, a second valve casing connected to the first-mentioned casing into which the latter discharges past the check valve, a shut-off valve 100 in the second-mentioned casing, and means for connecting said casing to a boiler to be supplied by the injector. 105

2. A valve comprising a casing having a valve seat at its outlet end and a passage leading to said seat from the inlet end of the casing, a check valve engageable with the seat, a nipple opposite the outlet end of the first-mentioned casing, a second valve casing connected to the nipple and having a

shut-off valve, a guide for the check valve held between the end of the first-mentioned casing and the adjacent end of the nipple, 10 and a coupling member connecting the nipple and the first-mentioned casing.

In testimony whereof I affix my signature.

HANS GUSTAV JOACHIM DEINERT.
